UNITED STATES PATENT OFFICE

2,131,522

REFRIGERATOR

Charles W. Peterson, Cincinnati, Ohio, assignor,
by mesne assignments, to The Crosley Radio
Corporation, Cincinnati, Ohio, a corporation of
Ohio

Application August 12, 1937, Serial No. 158,647

2 Claims.

(Cl. 62—89)

My invention relates to domestic food refrigerators which have shelves on the inside of the door, and the object of my invention is to partition off this shelf space from the dried air in

- 5 the main part of the refrigerator so that these shelves will be a suitable place to keep fresh vegetables, apples and other foods which wither or are harmfully dried out by the very dry air always present in refrigerators which are cooled
10 by a cooling unit kept colder than the freezing point of water. This door shelf space is not cooled by air convection currents from the main part of the refrigerator, as has formerly been the practice, for, being sealed tightly by the hinged
15 partition provided, it is cooled only by heat removed by conduction through the metal or other material out of which the partition is made.

Names such as "Humi-Shelvador", "Crispador", "Crisper-Shelvador" or "Humidoor" refrigerator would suitably describe refrigerators containing my improvement.

My invention may be clearly understood by reference to the accompanying drawing, in which:

Fig. 1 is a plan sectional view of the front part of the refrigerator at the door latch; Fig. 2, a side vertical section on line 2—2, Fig. 1; and Figs. 3, 4 and 5 are small vertical views of one type of suitable door handle and latch mechanism on lines 3—3, 4—4 and 5—5 respectively, Fig. 1; 30 Figs. 4 and 5 being sectional and enlarged for clarity.

Similar numerals refer to similar parts throughout the several views.

The refrigerator shown has the usual box 1 and door 2 of heat insulating material, and the usual cooling unit 3, tray 4 and shelves 5, Fig. 2. Three wire shelves 6 6 6 and a special tight shelf 7, Fig. 2, are all fastened to back side of door 2.

40 The special feature of my invention is the inner door, partition or cover 8, whose rim 9 seals against gasket 10 of back side of door 2 and against gasket 11 of refrigerator box 1. This inner door may be flat, slightly dished as shown, 45 or deeply pan shaped, depending on whether the back side of the refrigerator door is deeply recessed to fully cover the door shelves, moderately recessed to nearly cover the door shelves as shown, or flat; as a tight chamber entirely 50 covering the door shelves must be formed between door 2 and cover 8.

This inner door 8 is hinged at, or in line with, the main refrigerator door hinges 12, Fig. 1, so that the two doors may be swung as a unit or separately as desired. This selective opening of

the two doors is made possible by a special door handle and latch mechanism, one of many possible types of which is shown in the drawing.

This latch shown operates as follows:

If it is desired to open the main part of the 5 refrigerator leaving the door shelf space sealed, handle 13 is turned to R, Fig. 3, which turns door handle hook 14 out from under stationary hook 15, Figs. 1 and 5, releasing the door. Inner door 8 swings as a unit with outer door 2, as inner 10 door handle hook 16 remains behind latch hole edge 17 of inner door 8, Figs. 1 and 4. If it is afterward desired to open the door shelf space when the main part of the refrigerator is already 15 open, it is merely necessary to turn door handle 13 to D, Fig. 3 or if the handle 13 is not available because of the open position of the door, the hook shaped end 14 of handle shaft may be used 20 as a knob to move the shaft to the position equivalent to the position D at which the hook 16 is released from engagement behind the latch hole edge 17.

If it is desired to open the door shelf space 25 of the refrigerator leaving the main refrigerator space sealed, door handle 13 is turned to D, Fig. 3, which turns door handle hook 14 out from under stationary hook 15, Figs. 1 and 5, releasing the outer door, but inner door 8 does not open with it because inner door handle hook 16 turns to hole 18 in inner door 8, Fig. 4, and inner 30 door rim 9 is arrested by spring ball catch 19, Figs. 1 and 4. If it is afterward desired to open the main part of the refrigerator also, the inner door may be pulled open past ball catch 19 by one finger inserted in latch hole 35 18, Fig. 4, or by means of an inner door handle that may be provided.

Since the door shelf humidor chamber is cooled by heat being removed by conduction through the material of inner door 8 and not by the usual 40 air convection current method, it is a very simple matter to design this door shelf chamber so that the temperature at different shelves is different so as to be suitable for different kinds of foods. For instance: room temperature is too warm and 45 standard refrigerator temperature too cold for keeping bananas well. In Fig. 2, upper shelf 7 has been made a place of proper temperature for keeping bananas, by adding the right amount of heat insulating material 20 to the part of inner 50 door 8 enclosing this shelf, and by making this shelf solid so that convection currents of air from the lower door shelf space will not hinder.

In refrigerators that are opened and closed many times in a day, my invention adds consid- 55

erable economy of operation, for when the door shelf space only is opened, the cold air in the main part of the refrigerator is not lost; and when the main part of the refrigerator only is opened, the cold humid air of the door shelf space is not lost and the food in these shelves is not dried out.

What I claim as new and wish to protect by Letters Patent is:

10 1. A refrigerator including an outer door formed to provide a compartment and having shelves therein, an inner door movably mounted with respect to the other door to seal or expose said

compartment, said inner door having means thereon arranged to modify heat transfer there-through in the vicinity of certain of the shelves.

2. A refrigerator having an opening to a main compartment for the storage of food and including an outer hinged door formed to provide an auxiliary food storage compartment and having shelves therein, a hinged inner metal shield extending across the opening to the main compartment and means associated with said metal shield for modifying the heat transfer to various shelves in said auxiliary compartment.

CHARLES W. PETERSON.
